(57) **CLAIM**

The ornamental design for an ice cream packaging, as shown and described.

DESCRIPTION

FIG. 1 is a top perspective view of the ice cream packaging; FIG. 2 is a top plan view of the ice cream packaging; FIG. 3 is a side elevation view of the ice cream packaging. FIG. 4 is a bottom plan view of the ice cream packaging; and, FIG. 5 is a bottom perspective view of the ice cream packaging.

The broken lines are included for the purpose of illustrating a portion of the ice cream packaging that forms no part of the claimed design. It is understood that the appearance within the unshaded top and bottom end regions likewise forms no part of the claimed design.
